UNITED STATES PATENT OFFICE

WILLARD D. MILLER, OF EL PASO, TEXAS

DESIGN FOR A BOTTLE

Application filed November 8, 1932. Serial No. 45,841. Term of patent 7 years.

To all whom it may concern:

Be it known that I, WILLARD D. MILLER, a citizen of the United States, residing at 1973 Happer St., city of El Paso, in the county of El Paso and State of Texas, have invented a new, original, and ornamental Design for Bottles, of which the following is a specification, reference being had to the accompanying drawing, forming part thereof.

The figure is a side view in elevation of a bottle, showing my new design.

I claim:

The ornamental design for a bottle, as shown.

WILLARD D. MILLER.
